UNITED STATES PATENT OFFICE.

CARL GUSTAFSON, OF CHICAGO, ILLINOIS.

COMBINATION TELESCOPING AND FOLDING BUFFET-BED.

1,170,149.

Specification of Letters Patent.

Patented Feb. 1, 1916.

Application filed November 6, 1911. Serial No. 658,797.

To all whom it may concern:

Be it known that I, CARL GUSTAFSON, a citizen of the United States, residing at Chicago, in the county of Cook and State 5 of Illinois, have invented certain new and useful Improvements in Combination Telescoping and Folding Buffet-Beds, of which the following is a specification.

My invention relates more particularly 10 to improvements in combination telescoping and folding buffet beds, in which, the economical feature of telescoping the bed frame and folding the bed spring together with the mattress, within the telescoped bed 15 frame is employed, that the same may be folded within the sides of a buffet or other similar furniture, such as, side-boards, bureaus, chiffonniers, or the like.

Another object of my improvement is to 20 securely lock the bed in its open position, or, in other words, forcing, so to speak, a wedge between the foot-board of the telescoping bed frame and the bed spring frame, which, as will be seen, makes the extended 25 frame rigid and firm.

Other objects attained in my improvements will be more clearly pointed out in the drawings, the following specification, and the appended claims.

30 I attain these objects by the mechanism illustrated in the accompanying drawings, in which—

Figure 1, Sheet 1, is an outside perspective view of my invention, embodying my improvements. Fig. 2, Sheet 1, is an outside perspective view of my invention, partly disclosing my improvements. Fig. 3, Sheet 2, is an end elevation of Fig. 1, shown partly in section to disclose the bed in its folded, 40 telescoped and normally closed position. Fig. 4, Sheet 3, is a vertical cross section substantially central of Fig. 1, but showing the telescoping bed opened as for use, with the mattress removed. Fig. 5, Sheet 3, is a 45 section taken on line X—X of Fig. 4. Fig. 6, Sheet 3, is a section taken on line Y—Y of Fig. 4. Fig. 7, Sheet 3, is a section of the end of the telescoping bed frame at the foot, showing a method employed to make 50 up for a shortened spring frame when lower bureaus, etc., are desired.

Similar letters refer to similar parts throughout the several views.

In Figs. 1, 2, 3 and 4 respectively, (A) 55 represents in this instance, more particularly, a buffet or sideboard. It has, as will

be noted in the several views, two containing drawers (1). In the sides or ends (B) an opening (2) is made permitting the removal of the clothes hanger, or rack (C), from the compartment or wardrobe (D). The wardrobe compartment is inclosed by the sides or ends (B) and doors (E), and also by the partition (3), the back (4), and at the top by the top piece (5), and the bottom piece, 60 or floor (6). The reason of this construction is particularly to exclude as much dust and objectionable foreign matter from the wardrobe as is practically possible. The drawers (1) are inclosed similarly for the same purpose, as is the wardrobe; but instead of the floor (6), for the drawer, is a drawer compartment bottom (7). In the top of the compartment, or wardrobe (D), is securely 65 hung on the under side of the top piece (5), two Z bars, in such a manner (or preferably in the manner shown) to act both as a track and a guide upon which the rollers (C¹) of the clothes rack or hanger ride.

In the back (8), or that portion which 70 extends above the top piece (5), is pivotally secured a looking-glass (9); and also on the front side of said back (8) is hinged, as shown in Figs. 1, 2, 3 and 4, at (10), a shelf (11), having secured to the underside 75 thereof, pillars or columns (12), which rest upon the top piece (5). This feature of being able to raise the shelf and the supports (12) from the surface of (5), permits of placing a dresser scarf, doilies or the like, 80 over the entire top surface of said piece (5), if desired, or of readily removing said scarfs, etc., when they have become soiled.

In Figs. 1 and 2, below drawers (1, 1), are two small panels (13) and two large 85 panels (14) in the front side of (A); this virtually gives the appearance of two drawers and two doors, but in reality, they are merely imitation drawers and doors, and are in fact the bottom of the disappearing 90 or telescoping bed (15). The term "disappearing" is here used in the sense that when the bed is normally closed, the bed feature has disappeared, owing to the fact that the two imitation drawers and doors would 95 naturally lead one to believe that it is nothing more or less than (as in this case) a buffet, or sideboard. The bed (15) is pivotally hung on trunnions (16) secured to the sides (B) and (17) respectively. It 100 will be particularly noted by referring to Fig. 4, that it is impossible for the occupant 105

to be shut up accidentally by the bed closing of itself upon him.

The telescoping members (18) and (19) are shown in Fig. 4 in their extended position, but in Figs. 1, 2 and 3 they are telescoped. The main object of having a telescoping frame is that when the bed is in its normally closed position, it shall occupy the shortest space possible, and when opened 10 for use, shall extend to its proper or desired length.

Referring to the several views and particularly to Fig. 4, the bed (15) is composed of three sections (17), (18) and (19) 15 in which the bed spring frame (20) and (20¹) are contained and supported. In the end (21) of the frame (17), is a support (22) for supporting one end of the frame (20); and directly above the frame (20) is 20 a block (23), secured in each corner of the frame (17), through which a screw (24) is passed and fastened in the frame (20), as shown. This screw (24) holds the frame (20) from being pulled along with the sections (18) and (19), when they are being extended. It will be noted that the middle section (18) has a cross piece (25) upon which is secured a stiff spring (26). This spring (26) presses against the longitudinal 25 slats (27) with enough tension to retard the movement of the middle section (18), while the telescoping sections (18) and (19) are being opened or closed. In the section (18), on either side, is a rectangular opening (28), and on either side of the opening, a portion of the section (18) is cut away 30 to form a slideway (29). Through this opening (28), a projection (30) extends laterally from the sides of the section (19). 35 To the projection (30), is secured two upright pieces (31), which extend into the slideway (29); and to the ends of these uprights (31) is secured a cross connection (32). This construction not only acts as a 40 sliding guide, but also as a substantial support for both the ends of the sections (18) and (19), and also as a firm sliding connection between the two said sections. This construction also gives the advantage of 45 being able to telescope the sections in a very short space. The section (18) is slidably secured between the flanges (33) and the bottom (34) of the section (17). Section (19) has in one end a cross piece (35); and 50 to the inner sides of said section (19) is a strip (36) upon which is supported the bed spring frame (20¹) and on the underside of section (19) is secured a block (37) to which is secured a flexible strip (38), preferably leather, to prevent the spring (39) 55 from rubbing against the bottom (34) when the bed is being operated. The spring (39) is adapted to bring the foot (40) into the position shown in Fig. 4, when the bed is 60 being opened. The foot (40) is secured to

the undersides of (19), by hinge or hinges (41) attached thereto, and, is prevented from going beyond the vertical position by a stop pin (42) driven in the sides of section (19). To the frame (20¹) is secured 70 a U shaped angle iron or socket (42¹) which is adapted to fit over the end of the foot (40) preventing same from tipping over and letting the bed down on the floor. The frame (20¹) is further supported by a cross piece 75 (43) in the section (19). Section (19) has an end piece (44), to which is hinged a strip (45), which fills up the gap (46) between the frame (20¹) and the end piece (44). This gap (46), as can be readily seen, will 80 become greater or smaller according to the different heights desired in the pieces of furniture. In order to provide for various heights, several strips (45¹) are used, hinged together preferably, as shown in Fig. 7. 85 These strips are supported by lugs (47) secured to the frame (20¹). The section (17) has, on either side, feet (48), which pivotally hang and automatically drop into place. The bed spring frame (20) and (20¹), as 90 will be seen, are connected to each other by a compound hinge plate (49); this, as will be seen by referring to Fig. 3, permits of the mattress (50) to be folded between the two sections (20) and (20¹), when the bed 95 is folded and closed. The vertical corner strips or pilasters (51) are hinged to the buffet, and have (shown only in Fig. 2), a latch (52) controlled by an ordinary thumb piece (53) at the upper end thereof, of said 100 strips. These strips (51) hold or lock the bed in its closed position, by securing said strips by the thumb latch secured in socket (not shown), in the under side of the cross piece (54). 105

Referring to the drawings and the foregoing description, it will be seen that my improvements result in a very economical and useful piece of combination furniture; the same having a feature that is not overlooked by most of the buyers of folding beds—that is, safety to the occupant while sleeping, with the assurance that accidental death will not be met by the sudden and unforeseen closing of the bed. 110

Having thus described my invention, the merits of my improvements can be readily understood, and it will be seen that the minor details of my construction can be altered in many ways without departing from the spirit of my invention, but 115

What I claim and desire to secure by Letters Patent is—

1. In a combination telescoping and folding buffet bed, a bed casing, a folding compound telescoping bed frame comprising, a section pivotally hung to and within the sides of the bed casing, a plurality of sections telescopingly connected and each acting as a guide and support for the other, 125 130

- and telescopically connected to said pivotally hung section, a telescoping preventing means adapted to act as, both a lock and an extension between and against the bed 5 spring frame and the outermost extended telescoping bed frame section, a spring actuated bed frame support, a gravity actuated pivotally hung bed frame support, a bed spring frame section adapted to be folded together with the mattress, within the telescoped and folded, or closed bed frame within the sides of the bed casing, a second bed spring frame hinged to the first bed 10 spring frame section and detachably secured to said pivotally hung bed frame section, and against longitudinal movement with said telescoping sections.
2. In a combination telescoping and folding bed, a bed casing, a folding compound 15 telescoping bed frame comprising, a section, pivotally hung to and within the sides of the bed casing, sections telescopingly connected to one another and to and within said pivotally hung section, one of said sections adapted to slide within and be supported by said pivotal section, and, to act as a sliding connection and support for another telescoping section therewithin, substantially as described, a combination telescoping preventing means, and lock and extension member, adapted to act as a lock between the outermost extended telescoping section and the bed spring frame, and as an extension for shortened telescoping folding 20 bed frames, a bed spring frame section adapted to be folded together with the mattress, within the telescoped folded or closed bed frame within the sides of the bed casing, a second bed spring frame section hinged to the first bed spring frame 25 section and detachably secured to said pivotally hung bed frame section, and against longitudinal movement with said telescoping sections.
3. The combination in a combination folding and compound telescoping bed frame of, a bed casing, a bed frame section pivotally connected with the bed casing, telescoping sections interlockingly connect- 30 ed one within the other, one of said sections supported by said pivotal section, and adapted to act as a sliding guide and support for the other telescoping section, and adapted to be telescoped and folded, together with a folding bed spring frame section and a mattress, within the sides of the bed casing, bed spring frame sections detachably secured to said pivotally hung section, and against longitudinal movement with said telescoping sections, a combination telescoping preventing means, and lock and extension member, adapted to act as a lock between the outermost extended telescoping section and the folding bed spring frame section, and, as an extension for shortened telescoping folding bed frames, a spring actuated frame support and a gravity actuated pivotally hung section support. 35
4. The combination in a combination folding telescoping bed, of, a bed casing inclosing a telescoping folding bed frame consisting of a pivotally mounted section, an intermediate telescoping section slidably connected to and within and supported by the pivotal section, a second telescoping section interlockingly connected to and within and supporting the intermediate telescoping section, a compound folding bed spring frame having one section detachably secured to and supported within and upon said pivotal section, said compound bed spring frame adapted to support a mattress and to be folded together with the mattress and to envelop the same within the sides of said bed casing, and means for locking said telescoping folding bed frame in its open or extended position against the end of the folding bed spring frame, a spring actuated bed support adapted to support the bed in its open, or, extended position and a gravity actuated pivotal section support carried by said pivotal section. 40

CARL GUSTAFSON.
